CONVERTIBLE NECKLINE SLIP

Lee Parlette, Long Island City, N. Y., assignor to
Textron, Inc., New York, N. Y., a corporation of
New Hampshire

Application October 19, 1949, Serial No. 5,577

Term of patent 3½ years

(Cl. D3—26)

To all whom it may concern:

Be it known that I, Lee Parlette, a citizen of the United States of America and a resident of Long Island City, county of Queens, and State of New York, have invented a new, original and ornamental Design for a Convertible Neckline Slip, of which the following is a specification, reference being had to the accompanying drawing, forming part thereof, in which—

Fig. 1 is a front view of a convertible neckline slip embodying my design.

Fig. 2 is a rear view thereof.

Fig. 3 is a fragmentary view of a front portion of a slip shown in Fig. 1 with the button tabs released and turned under so as to show the neckline in converted position.

I claim:

The ornamental design for a convertible neckline slip, as shown and described.

LEE PARLETTE.
